UNITED STATES PATENT OFFICE.

JOSEPH AUGUSTUS ANGLADA, OF NEW YORK, N. Y., ASSIGNOR TO THE ANGLADA COMPANY, OF DETROIT, MICHIGAN, A CORPORATION OF MICHIGAN.

DEMOUNTABLE RIM.

1,146,122.

Specification of Letters Patent. Patented July 13, 1915.

Application filed March 7, 1913, Serial No. 752,584. Renewed December 2, 1914. Serial No. 875,185.

To all whom it may concern:

Be it known that I, JOSEPH A. ANGLADA, a citizen of the United States, and a resident of New York city, borough of Brooklyn, in 5 the county of Kings and State of New York, have invented certain new and useful Improvements in Demountable Rims, of which the following is a specification.

This invention relates to demountable 10 rims, particularly such as are used for vehicle tires.

In the ordinary forms of demountable rims, great difficulty has often been experienced due to the binding action of the movable element, making it difficult to readily remove the rim from the wheel. Also difficulty has often been experienced in obtaining a snug fit of the rim about the wheel at 15 all points and thus considerable annoyance 20 resulted due to the wearing and rattling of the parts. In certain cases where attempt has been made to overcome these defects, resort has been had to a plurality of adjustments which made it a tedious and laborious 25 matter to mount the rim upon the wheel and also in many cases it has been found difficult to readily remove the rim when once mounted and clamped in position.

The present invention has for its principal 30 object to overcome these difficulties and to this end, I provide a somewhat flexible resilient wedging member which is inserted between the rim and felly and which may, if desired, be actuated by a single actuating 35 member to cause the successive portions of the wedging member to wedge in between the rim and felly, so as to clamp the rim to the wheel and also rigidly support the same in a radial direction at all points about the 40 circumference of the wheel. Also when the rim is to be removed, this single actuating member serves to unclamp successive portions of the same wedging member and thus makes it easier to unclamp the rim from the 45 wheel, as the resistance offered to the release of the wedge is merely that of the individual portions of the length of the flexible wedging member, and thus the resistance at any given instant during the releasing operation is a 50 fraction of the total resistance offered by the entire wedging member. Preferably, I make this wedging member in the form of a split ring of spring metal and the actuating member operates by drawing this ring circumfer-

entially about the wheel. The ring may be 55 normally either of slightly larger or slightly smaller diameter than the felly. Thus when it is first inserted between the rim and felly and pulled circumferentially from one end, the farther end will be the first to be brought 60 into firm engagement between the felly and rim, and as the pull is increased, successive portions of the wedge are brought into firm engagement until the entire length of the wedge is in proper position and the rim is 65 firmly clamped to the wheel. According to my preferred construction, the wedge in moving circumferentially about the felly is guided so as to receive a lateral movement which results in the wedging action, and the 70 same actuating mechanism which is used for actuating the wedge into engagement is also used for positively actuating the wedge out of engagement with the felly band and rim so as to unclamp the latter. In such construction, the successive unclamping of portions of the wedge is readily accomplished.

In addition to the advantages set forth above, the construction is inexpensive, light, efficient, and not liable to get out of order.

Various further objects and advantages will more fully appear from the detailed description and the features of novelty in construction and combination of parts will be particularly pointed out in the claims.

In the accompanying drawings illustrating the preferred forms in which this invention may be carried out, Figure 1 is a transverse section taken through a wheel embodying my invention. Fig. 2 is a longitudinal section with portions broken away for the sake of clearness. Fig. 3 is a detail view illustrating a section of the clamping ring and the actuating eccentric. Fig. 4 is an enlarged sectional detail illustrating the 95 movement of the clamping ring from the position it assumes when first inserted to the position it assumes when it is firmly clamped. Fig. 5 is a sectional detail illustrating a modified form of ring applied to another 100 form of rim. Fig. 6 is a sectional detail view, and Fig. 7 is a fragmental plan view illustrating a modified form of actuating device for the clamping ring. Fig. 8 is a sectional detail view illustrating my improvement applied to a wire wheel. Figs. 9 and 10 are respectively an elevation and side view of another form of clamping ring.

Fig. 11 is a detail view illustrating a locking device for the ring illustrated in Figs. 9 and 10. Fig. 12 is a fragmental detail view illustrating another form of actuating device for the clamping ring. Fig. 13 is a fragmental sectional detail view illustrating partly in perspective still another modified form of rim and clamping ring. Fig. 14 is a fragmental detail view illustrating the clamping ring used in the construction shown in Fig. 13. Figs. 15 and 16 are fragmental sectional detail views illustrating further modifications.

Referring in detail to Figs. 1 and 4, the felly 10 of the wheel has the usual band 11 provided at one side with a flange 12 against which is clamped the demountable rim 13. Lugs or shoulders 14 and 15 attached to or formed respectively on the band and rim interengage so as to prevent the rim from creeping about the wheel. For clamping the rim rigidly against the flange 12, I provide the following means: Formed upon the band 11 are a plurality of projections or pins 16. A split clamping ring 17 formed of spring sheet metal is adapted to engage the periphery of the band and the free edge of the rim so as to simultaneously wedge in between the band and rim and to clamp the latter against the flange 12. This ring 17 has a substantially annular portion 18, the interior of which is normally of slightly greater diameter than the periphery of the band 11 as indicated in dotted lines in Fig. 4, or the ring may be normally of slightly less diameter than the diameter of the band. In the latter event, when the ring is inserted upon the band, portions of the same will so be spaced out of contact with the band, as will be readily understood. An inclined flange 19 extends outward from the annular portion and engages the free edge of the rim 13, so that when the clamping ring is forced inward, it wedges in between the rim and band and thus simultaneously supports the same radially and clamps it against the flange 12. For forcing the clamping ring inward while being moved circumferentially, the following construction is provided: Formed in the annular portion of the clamping ring are a plurality of inclined slots 20 having mouths 21 registering with the projections or pins 16 upon the band. The mouths 21 preferably extend laterally of the ring and form openings through which the pins may enter into the inclined slots by a lateral movement of the ring with reference to the wheel when the ring is inserted manually over the latter. A curved portion 21^a forming a continuation of the wall of the mouth and slot serves as a guide which operates upon the rotational movement of the ring to guide the pins into the inclined slots. When the ring is thus inserted between the rim and band as shown in dotted lines in Fig. 4, and

then pulled at one end, the farther end of the ring will first wedge itself in by reason of the engagement of the pin within its inclined slot. The action corresponds to the tightening of a spring wire about a wheel. The portion farthest from the end pulled is the first to hug the wheel. As the pull upon the one end of the ring is continued, the successive portions of the ring wedge themselves in by reason of the engagement of the pins in the successive slots until the entire ring is firmly wedged in place and clamps the rim to the felly and properly supports its free edge. It will be readily seen that by this action of the clamping ring, a small force only is required to properly adjust the clamping ring, inasmuch as the resistance is offered by the small portions of the ring successively. In this way, assurance is had that no binding action on the part of the ring will prevent its proper adjustment. It will be noted that by reason of this gradual engagement of the clamping ring, it will also be easy to unclamp, as it will disengage gradually in the same manner as it is brought into engagement. Thus, if the parts should rust or clog, no difficulty will be experienced in loosening the same. For actuating the ring, any desired means may be employed. Preferably, I form the ring with a slot 22 into which extends an eccentric 23 mounted upon a pin or bolt 24 provided with a squared end 25 by which the bolt may be actuated. A tapered head 26 is preferably formed upon the bolt to engage the band and a lock nut 27 is preferably mounted upon the inner end of the bolt to clamp the same in adjusted position.

In the modified construction illustrated in Fig. 5, the clamping ring 30 is formed with a channeled portion 33 to engage the shoulder 34 formed upon the band 35 which together with the rings 36 and 37 constitutes the rim. The ring 37 is held in place by the locking member 38, as will be readily understood. The clamping ring 30 engages the pins 39 projecting from the band 40 mounted upon the felly 41, substantially as in the construction as illustrated in Figs. 1 to 4.

In Fig. 6, I have illustrated a modified form of actuating device for the locking ring consisting of a lever 42 having a fulcrumed portion 43 engaging the flange 12 in an aperture formed therein, the shoulders 44 of which constitute fulcrum points for the lever. The load end 45 of the lever engages within the slot 22 formed in the ring 17. The locking pin 24 with its eccentric 23 engages the lever substantially in the same manner as it engages the clamping ring in the preferred construction.

In the form of the invention illustrated in Fig. 8 as applied to a wire wheel, the bolt 24 is considerably shortened so as to corre-

spond to the thickness of the band 11. Otherwise the construction is similar to the preferred form illustrated in Figs. 1 to 4.

In Figs. 9 to 11, I have illustrated a clamping ring which is split to form a plurality of segments 50, 51, 52 and 53. The slots 54 in the adjacent segments engaging the pins 55 are formed in opposite directions, so that when two adjacent segments are pulled toward each other by any desired means as for instance a lever 56 and link 57 (Fig. 9), the segments will clamp substantially as in the preferred construction. When the segments are so clamped, a locking device consisting of a bar 58 having a screw 59 extending therethrough at one end and a lug 60 extending therefrom at the opposite end, may engage in correspondingly formed apertures 61 and 62 at the ends of the adjacent segments, thus locking the latter in position.

In Fig. 12, I have illustrated another modified form of actuating device for the clamping ring. This actuating device consists of a pinion 63 mounted upon a pin 64 suitably positioned on the felly or felly band. The pinion meshes with a rack 65 formed on one end of the clamping ring 17. As the squared end of the pin 64 is engaged to rotate the pinion, the pinion actuates the clamping ring and thus pulls it so as to cause the ring to wedge in by the engagement of the slots and peripherally disposed pins, as will be readily understood from the description of the other forms of the invention.

In the modification illustrated in Figs. 13 and 14, the rim 70 is formed with the inclined inner surfaces 71 and 72, the former abutting an inclined shoulder 73 formed upon the band 74 attached to the felly. The band is also formed with inclined slots 75 at the side opposite to the inclined shoulder 73. The clamping ring 76 has an outer inclined face 77 which is adapted to engage the inclined face 72 of the rim and is also provided on its inner surface with a plurality of inclined lugs 78 which register with the inclined slots 75 of the band. When the ring is pulled circumferentially by the action of the eccentric 23 on the stem 25, the ring will by reason of the engagement of the inclined lugs and slots be moved inwardly to clamp the rim against the inclined shoulder 73.

In the form illustrated in Fig. 15, the rim 80 is formed with the inner inclined faces 81 and 82, the former of which engages the inclined shoulder 83 formed upon the band 84. The edge of the band 84 opposite to the edge having the shoulder 83 is inclined inwardly and is formed with a plurality of inclined slots 85 in which register inclined lugs 86 formed on the clamping ring 87. The latter is formed with inner and outer inclined faces 88 and 89 which engage re-

spectively the inclined edge 84 of the band and the inclined face 82 of the rim. In this way, a double wedging action is obtained due to the two inclined surfaces of the ring which coöperate with the correspondingly inclined surfaces of the band and rim.

In the form illustrated in Fig. 16, the band 90 is formed with inclined slots 91 and the clamping ring 92 is provided with the inwardly extending pins 93 registering with the slots 91. This form illustrates how the inclined slots and pins may be transposed upon the band and clamping ring as compared with the construction illustrated in Fig. 1.

It will thus be seen that I have provided a demountable rim which may be readily clamped and unclamped by a single actuating member, whereas the resistance offered during the clamping and unclamping action is not at any one time the total resistance of the wedge, but is the resistance of a portion of the wedge, as consecutive portions of the latter are brought into and out of engagement with the felly band and rim through the action of the single actuating member. Also assurance is always had that the wedge fits the rim and felly band at all points inasmuch as the wedge consists of a split ring, the various portions of which may readily adapt themselves to any inequalities which may exist in the rim and felly band, and thus the rim is supported at all points about the wheel and any rattling and resulting wear and noise are effectually obviated. Moreover, the construction is light and inexpensive and is very readily and cheaply manufactured.

Having thus described my invention, I claim—

1. In a wheel, a band provided with a flange or raised portion at one edge, a rim adapted to be clamped to the flange, a split clamping ring of spring material engaging the rim and band, said clamping ring having an interior diameter which normally differs from the diameter of the periphery of the band, said ring and band having inter-engaging members spaced about their circumference, and means for actuating one end of the ring so as to cause said inter-engaging members to successively engage so as to cause the clamping ring to wedge itself in between the band and rim and simultaneously clamp the latter against the flange and also radially support the free edge of the rim.

2. In a wheel, a band provided with a flange at one edge, a rim adapted to be clamped to the flange, a split clamping ring of spring material engaging the rim and band, said clamping ring having an interior diameter which normally differs from the diameter of the periphery of the band, said band having a plurality of projections

spaced about its periphery and said ring having a plurality of slots registering with said projections, and means for actuating one end of the ring so as to cause the slots to come successively into engagement with the projections.

3. In a wheel, a band provided with a flange at one edge, a rim adapted to be clamped to the flange, a split clamping ring 10 of spring material engaging the rim and band, said clamping ring having an interior diameter which normally differs from the diameter of the periphery of the band, said band having a plurality of pins spaced 15 about its periphery and said ring having a plurality of inclined slots registering with said pins, and means for actuating one end of the ring so as to cause the slots to come successively into engagement with the pins.
4. In a wheel, a band provided with a flange at one edge, a rim adapted to be clamped to the flange, a split clamping ring 20 of sheet spring material having an annular portion, an inclined flange extending from one edge thereof, said clamping ring having an interior diameter which is normally larger than the diameter of the periphery of the band, said ring and band having 25 inter-engaging members spaced about their periphery, and means for actuating one end of the ring so as to cause said inter-engaging members to successively engage so as to cause the inclined flange to wedge itself in between the band and rim and simultaneously clamp the latter against the flange 30 of the band.
5. In a wheel, a band provided with a flange at one edge, a rim adapted to be clamped to the flange, a split clamping ring 35 40 of spring material engaging the rim and band, said clamping ring having an interior diameter which is normally larger than the diameter of the periphery of the band, said ring and band having inter-engaging mem-

bers spaced about their circumference, an eccentric engaging one end of the clamping ring to actuate the latter so as to bring the inter-engaging members successively into and out of engagement for gradually clamping or unclamping the rim to the flange, 50 and means for locking the eccentric.

6. In a wheel, a band provided with a circumferential shoulder, a rim adapted to fit said shoulder, a split clamping ring disposed between the rim and the band, said ring being provided with an inclined circumferential shoulder engaging the rim, means for rotating the ring to cause it to wedge in farther between the rim and band and clamp the rim against the band, means 60 for locking the ring in adjusted position, the means for rotating the ring being also adapted to free the ring from the wheel, said means imparting to the ring simultaneously, circumferential, lateral and radial movement.

7. In a wheel, a felly, a band attached to the felly provided with a circumferential shoulder, a rim adapted to be inserted over the band to abut said shoulder, a split 70 clamping ring adapted to wedge in between the rim and band, one of the latter being provided with spaced projections and the other being provided with correspondingly registering slots having a portion thereof 75 inclined relatively to the plane of the wheel, and another portion thereof extending laterally thereof, and means for rotating the ring relatively to the band so as to wedge the same between the band and rim. 80

Signed at New York city, in the county of New York, and State of New York, this 1st day of March A. D. 1913.
